(57) **CLAIM**

We claim the ornamental design for an ultrasound probe, as shown and described.

DESCRIPTION

FIG. 1 is a front view of an ultrasound probe showing our new design;

FIG. 2 is a back view of the ultrasound probe design shown in FIG. 1;

FIG. 3 is a left view of the ultrasound probe design shown in FIG. 1;

FIG. 4 is a right view of the ultrasound probe design shown in FIG. 1;

FIG. 5 is a top view of the ultrasound probe design shown in FIG. 1;

FIG. 6 is a bottom view of the ultrasound probe design shown in FIG. 1;

FIG. 7 is a front perspective view of the ultrasound probe design shown in FIG. 1;

FIG. 8 is a back perspective view of the ultrasound probe design shown in FIG. 1;

FIG. 9 is a front perspective view of the ultrasound probe design shown in FIG. 1; and,

FIG. 10 is a front perspective view of the ultrasound probe design shown in FIG. 1.

In these drawings, the solid lines illustrate the claimed ornamental design, whereas the broken lines illustrate unclaimed environmental features and form no part of the claimed design.
